UNITED STATES PATENT OFFICE.

RAUL PATERAS PESCARA, OF PARIS, FRANCE, ASSIGNOR, BY DIRECT AND MESNE ASSIGNMENTS, TO THE PESCARA & RAYMOND CORPORATION, OF DOVER, DELAWARE, A CORPORATION OF DELAWARE.

INTERNAL-COMBUSTION-MOTOR COMPRESSOR UNIT.

Application filed August 18, 1924, Serial No. 732,811, and in France June 11, 1924.

The present invention relates to motor compressor units in which the transformation of energy into work is effected without any kinematic connection of the piston intended to transform a reciprocating movement into a rotary movement, said apparatus deriving the energy necessary for their operation from combustion taking place within the apparatus themselves.

10 Apparatus of this kind are for example motor compressor units, apparatus in which the compression of the gases or vapours is effected in a chamber, either cylindrical or having the shape of a torus, the volume of which is made variable by means of the movements of one or more tight pistons arranged in said chamber, with this characteristic feature that the said pistons are independent of any kinematic connection and 15 that their reciprocating movements are sustained solely by the suitably controlled expansion of gas at high temperature coming from combustion effected in the cylinder (or torus) itself.

20 It consists first of all in providing this type of apparatus with a device, entirely or partially actuated, for distributing and eventually igniting the motive or compressed fluids and enabling the gases therein to be caused to follow a judiciously arranged cycle, said cycle being of the type known as explosion or combustion, single or double acting and comprising eventually, the necessary scavenging of the combustion gases either 25 mixed or not at certain moments with the gases to be compressed, while certain strokes of the piston can be effected under the impulse of elastic members, such as for example a buffer of gas retained at the end of 30 the stroke within the corresponding chambers and thus playing the part of returning springs, and finally ensuring balancing of the moving masses within the variable chambers either by the arrangement of two pistons always moving in opposite directions, or by the conjugation of two single-piston apparatus in which the pistons move respectively in opposite directions, and finally to obtain synchronism of the movement of 35 the two pistons (whether these two pistons move in the same chamber or in two separate chambers) by a device which may be auto-

matic or driven by a suitable conjugation of the distributing or ignition mechanisms.

The invention, which has been described above in a general manner, comprises a large number of special applications coming under the scope thereof, while all apparatus utilizing the principle of the said process and separate parts thereof are also protected thereby.

The invention will be readily understood with the help of the following description and the drawings annexed thereto, which of course, are only given by way of example.

The accompanying drawing represents a longitudinal diagrammatic section of a self-compressor motor according to the invention.

According to the invention and more especially according to that form of execution to which the figure refers (supposing that it is required to construct a self-compressor motor utilizing petrol according to the two-stroke explosion cycle) the apparatus can be constructed as follows or in a similar manner.

In a cylindrical chamber 10 there can move two tight pistons 11 and 12 which are entirely free. The cylinder 10 also comprises a plurality of ports, of which 13 represents inlets of carburetted air which are closed by automatic valves, such as 14 and communicating with the suction nozzle of a carburettor 9.

The exhaust ports 15, 16 are closed by valves, such as 17, 18, the lift of said valves being controlled by small pistons 19, 20, on the face of which acts the pressure existing at the extremities of the cylinder, which is made to act on said small pistons by means of tubes 21, 22 opening into the cylinder at 23, 24. The closing of the valves is effected by the returning springs 25, 26.

The apparatus is provided with three valves such as 17 and three others such as 18.

Inlets 27, 28 for air from the atmosphere are placed in the cylinder heads and each is fitted with an automatic valve 29, 30. 31 and 32 represent ports for the discharge of the compressed air, these ports being controlled by automatic valves 33, 34.

This apparatus does not comprise any elements for auxiliary ignition, the combustion of the mixture being caused by spontaneous

combustion due to the rise in temperature produced by the preliminary compression which is sufficiently high.

The self-compressor motor operates in the following manner:

- 10 The two pistons 11 and 12 are first forced sufficiently close together to compress between them and ignite at high pressure a combustible mixture which has been injected into the space between the pistons. This initial movement of the pistons may be accomplished by injecting compressed air from the reservoir into the ends of the cylinder. For example, the valves 33 and 34 may 15 be provided with lever 33^a and 34^a by means of which the valves can be manually opened against the resistance of the springs to admit compressed air to each end of the cylinder.
- 20 When the combustible mixture ignites, the pistons are forced in opposite directions, toward the ends of the cylinder, by the expansion of the burnt gases and compress the fresh air, which, at this moment fills the cylinder heads.

Each piston therefore comprises a driving face and a face serving for compression. We will first examine what takes place on 30 the side of the driving face. The burnt gases expand from the central position of the pistons until the inner faces of these latter pass beyond the edge of the ports 15, 16.

- 35 At this moment the valves 17, 18, open under the pressure existing in the cylinder-heads and acting upon the pistons 19, 20. The burnt gases then escape suddenly and leave behind them a certain vacuum caused by their inertia, and increased by the continuation of the movement of the pistons in view of the velocity acquired. The automating valves 14 then open and allow a 40 fresh charge of carburetted air to enter the cylinder which fills this latter up to the ports 15 and 16. During this time the pistons 11 and 12 have arrived at the end of their stroke and imprison, between their outer faces and the cylinder-heads, a certain 45 quantity of compressed air which damps their movement and stops it.

Under the action of the gaseous buffer thus retained at the end of the stroke, the pistons move again in the opposite direction, driving before them and expelling from the cylinder all that remained of the burnt gases 50 between the ports 15 and 16 and their internal faces.

During this time the valves 17, 18 have remained open, since the ports 23, 24 were 60 closed by the pistons and did not permit of the evacuation of the compressed air acting upon the small pistons 19, 20; at the moment when the inner faces of the pistons 11, 12 register with the ports 15, 16, the exhaust valves 17, 18 close.

The pistons 11, 12 then continue their stroke in the opposite direction and towards each other, compressing the carburetted mixture comprised between them, while the automatic valves 14 close the orifices 13 as 70 soon as the pressure between the pistons reaches atmospheric pressure. As the gaseous buffer provided at the end of the expansion stroke of the pistons 11, 12 between these latter and the heads of the cylinder 75 10 is calculated to provide them with kinetic energy sufficient to cause a compression resulting in spontaneous ignition of the carburetted mixture, the same cycle of operations continues indefinitely.

By their outer faces, the pistons driven by the expansion of the burnt gases, compress the fresh air contained in the cylinder-heads, until the automatic valves 33 and 34 open and permit of the discharge at constant pressure of the compressed air into the reservoir.

This operation continues until the pistons pass the ports 31, 32. Starting from this moment, their momentum is deadened and absorbed by the gaseous buffers comprised between the said pistons 11, 12 and the cylinder-heads. These gaseous buffers then play the part of returning springs and force the pistons towards the centre, at the same time expanding to atmospheric pressure.

Of course the automatic valves 33, 34 close as soon as the pressure in the cylinders falls below the discharge pressure and this takes place automatically when the pistons return before the ports 31, 32.

When the gaseous buffer has expanded down to atmospheric pressure, the automatic valves 29, 30, open the ports 27, 28 and allow a further quantity of fresh air for the following compression to enter up to the end of the stroke of the pistons.

In this manner, a two-stroke cycle self-compressor motor is obtained, with spontaneous ignition and distribution by means of automatic valves, as regards the admission of fresh air and carburetted air and the discharge of the compressed air, while the valves controlling the exhaust of the burnt gases are actuated by the pressure of the compressed air. In the compressor in question balancing of the masses in movement is obtained by the arrangement of two pistons acting in opposite directions.

In an apparatus of this kind the synchronization of the pistons is obtained automatically owing to the arrangement of the combustion chamber in the centre of the machine, without it being necessary to have recourse to a positively operated device for ignition or distribution.

Any irregularity in the movement of the pistons would have, as its consequence, the ignition of the carburetted mixture at a time when the pistons 11, 12 would not occupy

positions equidistant from the centre of the cylinder. The driving power of the combustion gases is distributed however, always equally between the two pistons. On the other hand, if the resistances vary, the piston which was nearest to the cylinder-head has compressed and discharged less compressed air than the other. It therefore deadens upon the buffer a greater amount of kinetic energy and returns more rapidly towards the centre. The stoppage of the two pistons therefore takes place in a more correct position and the same phenomenon is repeated up to perfect synchronism.

15 It is obvious that the invention is not in any way limited to the form shown more specifically and many kinds of modifications are possible.

I claim:

20 1. A motor-compressor comprising in combination: two pistons, a cylinder closed at both ends and in which the pistons slide freely, means for admitting carburetted air in said cylinder between said pistons, exhaust ports in said cylinder at two points between its ends, valves closing said ports, air inlets in the closed end portions of said cylinder, automatic valves closing said air inlets, air discharge ports in said cylinder 25 between said exhaust ports and said cylinder ends, automatic valves closing said air discharge ports, and means for causing the valves controlling said exhaust ports to open under the action of the pressure in the closed 30 cylinder ends, all of said ports being controlled by the respective pistons.

25 2. A motor-compressor comprising in combination: two pistons, a cylinder closed at both ends in which the pistons slide freely, 35 means for admitting carburetted air in said cylinder between said pistons, exhaust ports in said cylinder at two points between its ends, valves closing said ports, air inlets in the closed end portions of said cylinder, automatic valves closing said air inlets, air discharge ports in said cylinder, between said 40 exhaust ports and said cylinder ends, automatic valves closing said air discharge ports, a piston connected to each of the valves controlling said exhaust ports, a cylinder for each last named piston, a conduit connecting each cylinder to the main cylinder, at a point between the corresponding exhaust port thereof and the closed end thereof, all of said 45 ports and conduits being controlled by the respective main pistons.

30 3. In a motor-compressor, a piston, a closed cylinder in which said piston slides freely, means for admitting motive fluid on one side of said piston, an exhaust port in said cylinder at a point between its ends, a valve closing said port, and means for caus-

ing said valve to open under the action of the pressure on the other side of the piston, and means actuated by said piston for compressing air. 65

4. In a motor-compressor, a piston, a closed cylinder in which said piston slides freely, means for admitting motive fluid on one side of said piston, an exhaust port in 70 said cylinder at a point between its ends, a valve closing said port, means for causing said valve to open under the action of the pressure on the other side of the piston, said port being controlled by the piston, and means actuated by the piston for compressing air. 75

5. In a motor-compressor, a main piston, a closed main cylinder in which said main piston slides freely, means for admitting motive 80 fluid on one side of said piston, an exhaust port in said cylinder at a point between its ends, a valve closing said port, a piston connected to said valve, a cylinder for said piston, a connection from said cylinder to the main cylinder and opening therein at a point between said exhaust port and the cylinder end opposite the other side of the main piston, said port and connection being controlled by said main piston, and means actuated by said main piston for compressing air. 85

6. In a motor-compressor, a piston, a cylinder in which said piston slides freely, means for admitting motive fluid to the cylinder at one side of said piston, the cylinder at the other side of said piston being closed to serve as an air compressor, inlet and outlet air valves in this closed end portion of the cylinder, an exhaust port for the motive fluid communicating with the cylinder at a point between its ends, a valve closing this port, a pressure responsive device for opening said valve, and a conduit connecting this device with the compression 95 space between the exhaust valve and the closed end of the cylinder. 100

7. A motor-compressor comprising in combination, two pistons, a cylinder closed at both ends and in which the pistons slide freely, means for admitting motive fluid to the space between said pistons, inlet and outlet air valves communicating with the spaces between the pistons and the closed ends of the cylinder, exhaust ports for the motive fluid communicating with the cylinder at points intermediate its central portion and its closed ends, valves for closing the exhaust ports, pressure responsive devices for opening the exhaust valves, these pressure responsive devices being in operative communication with the compression spaces at the ends of the cylinder. 115
